(57) **CLAIM**

We claim the ornamental design for wheel for a vehicle, as shown and described.

DESCRIPTION

FIG. 1 is a perspective view of a wheel for a vehicle showing our new, original, and ornamental design;
FIG. 2 is a front view thereof;
FIG. 3 is an upper perspective view thereof;
FIG. 4 is a side perspective view thereof;
FIG. 5 is a rear perspective view thereof;
FIG. 6 is a bottom perspective view thereof; and,
FIG. 7 is a rear view thereof.

The dash-dash broken lines in the drawings illustrate portions of the wheel for a vehicle that form no part of the claimed design.

The dash-dot broken lines in the drawings define the bounds of the claimed design and form no part thereof.
